ELECTRON-MULTIPLIER SYSTEM

Richard L. Snyder, Jr., Glassboro, N. J., assignor
to Radio Corporation of America, a corpora-
tion of Delaware

Application July 30, 1938, Serial No. 222,186

7 Claims. (Cl. 250—41.5)

My invention relates to electron discharge devices, particularly to electron multipliers and has special reference to the provision of improvements in the construction and operation of high gain photo-actuated electron multipliers.

One of the principal difficulties encountered in the use of electron multipliers is that of maintaining the gain of the device at a constant value irrespective of changes in the tube characteristics during operation and in spite of variations in the line voltage.

Accordingly, an object of my invention is to obviate the above described and other disadvantages incident to the use of electron multipliers.

Another object of my invention is to provide an improved electron multiplier and one which lends itself readily to the regulation of its gain.

Another object of my present invention is to provide a novel method of regulating the gain of an electron discharge device.

Other objects and advantages together with certain details of construction and operation will be apparent and the invention itself will be best understood by reference to the following specification and to the accompanying drawing wherein the single figure is a partly diagrammatic perspective view of a multistage electron multiplier energized and operated in accordance with the principle of the invention.

My invention is predicated upon my discovery that when electron current passes through an electron multiplier (for example, of the type disclosed in copending application Serial No. 205,672, to Pike et al., filed July 7, 1938) there is very little transverse spreading of the electron stream. That is to say, if a spot of light is focused on one side of the center of a photo-cathode, the anode will receive the multiplied electron current only on that side. Similarly, if two beams of light are directed upon the cathode, one on one side of its center and one on the other, two discrete electron streams will be generated. The separation between the streams will be maintained throughout the tube and if two anodes are provided two discrete output currents are produced.

Accordingly, my present invention contemplates and its practice provides an electron discharge device having an auxiliary anode. A modulated and an unmodulated beam of light are provided for generating two electron streams which eventually impinge upon the separate anodes. Small changes in the unmodulated current present on the auxiliary anode are utilized to vary the actuating voltage applied to a "con-

trol" electrode whereby to oppose the original change. The electrode thus controlled may comprise an intermediate multiplying electrode and the controlling voltage applied thereto, from the auxiliary anode, may operate to defocus or refocus the main electron stream, whereby the number of electrons impinging upon the main anode, and hence the modulated output current of the device, is regulated.

In carrying the invention into effect, I may employ an electron-multiplier similar to that described in the above mentioned application Serial No. 205,672 but modified to include a bi-part output electrode assembly. An electron-multiplier which has been thus modified, is shown in the accompanying drawing.

The electron multiplier of the drawing comprises a highly evacuated envelope T, which, for purposes of this description, may be considered to contain a longitudinal reference axis A—A. Suitably mounted adjacent one end of the axis A—A are two anodes, B, B', respectively, which are arranged in parallel relation on opposite sides of the axis. Mounted adjacent the other end of the axis A—A is an "oversize" photosensitive cathode C. A pair of sets of curved substantially L-shape multiplying (i. e., secondary electron emissive) electrodes are mounted on opposite sides of the reference axis between the cathode and bi-part anode. The electrodes of the "upper" set are odd-numbered 1, 3, 5, 7 and 9, and those of the "lower" set are even numbered 2, 4, 6 and 8.

The long leg of each L-shaped multiplying electrode, except electrode 1, extends across the axis A—A with its free end inclined toward the cathode. The short leg of each of the said L's extend in the direction of the anodes and each terminates at a point substantially equally distant from the said reference axis. As more fully described in the previously identified Pike et al. application, the contour of the cathode C preferably differs from that of the first multiplying electrode 1 and the contour of the electrode 1, preferably, but not necessarily, differs from the contour of the other multiplying electrodes. However, all of the electron emissive electrodes are of cylindrical curved construction and are mounted with the generatrices of their surfaces normal to a plane containing the reference axis A—A. The hollow box-like metal member S which forms a continuation of the surface of the cathode is designed to prevent wall charges (on the glass) from affecting the motion of the pho-

toelectrons in the region where their velocities are low, but may be omitted, if desired.

The potential distribution preferably employed during normal operation may be expressed by the mathematical series $1V$, $2V$, $3V$, $4V$, $5V$, etc., where $1V$ is the potential drop between the first target or multiplying electrode 1 and the photosensitive cathode C , and $2V$, $3V$, $4V$, etc., represent the potential drop between the respective 10 succeeding electrodes in point of electron travel and said cathode.

For the purpose of providing such a potential distribution, a voltage divider comprising two series connected resistors R , R' and a group of 15 resistors $r1$, $r2$ and $r3$, which are connected in parallel with R and R' , is provided. The anodes B , B' are normally maintained at approximately the same voltage ($10V$) by the potential drop developed, respectively, across resistors $r1$ 20 and R' . The cathode C is connected to the negative terminal of the direct current source by a lead c and the first multiplying electrode is connected to a point on R , indicated at $1V$ somewhat more positive than the cathode. The other electrodes 2 to 9 , inclusive, in the order of their numbers, are shown connected to successively more positive points on the voltage divider. The reference characters $1V$, $2V$, $3V$, etc., given to the several points on the resistors R and r will be 30 understood to indicate that the voltage drop between the given electrode and the cathode is the designated whole number multiple of the drop existing between the cathode and the first multiplying electrode 1 . Thus, where the potential drop between the first multiplying electrode 1 and the cathode C is 100 volts, the drop between electrodes 3 and C should preferably be 300 volts, that between the output electrode B and the cathode, 1000 volts.

40 In accordance with my invention, two separate light beams are directed upon the photosensitive surface of the cathode C to there give rise to two discrete streams of photo-electrons. The separate light beams may be derived from a common source exemplified by a lamp L , in which case a lens M may receive some of the light directly, and another lens N receive some of the light indirectly through a prism P . The lenses M and N are preferably so arranged with respect to the 45 cathode C that the beams are directed to points which are laterally well spaced from each other on the photosensitive surface of C . One of the light beams, in this case the beam from the lens M , may be modulated as by passing the light 50 through a moving picture film F which is suitably interposed in the space between the lens M and the photosensitive surface of the cathode C . The quantity of electrons released by the impress of the modulated light beam upon the 55 cathode will, of course, be determined by the instantaneous intensity of that beam when it has passed through the film. On the other hand, the unmodulated light beam and the electron stream generated thereby may reflect such variations as may be caused by an alternating current component in the lamp energizing circuit, or such as may be due to deterioration of the lamp filament as a result of prolonged use.

60 The photoelectrons released from the cathode by the separate light beams are accelerated toward the first "upper" electrode 1 , and because of the described design, relative arrangement, and voltage distribution, will impinge upon this first multiplying electrode in the form of separate electron beams. The separate photoelec-

tron streams striking electrode 1 , on opposite sides of its center, will cause the emission of two streams of secondary electrons, the number of electrons in each stream being dependent upon the intensity of the impinging primary 65 stream.

The next electrode in point of electron travel is the second "lower" electrode 2 . The trajectories of the secondary electrons constituting the discrete electron streams from the first multiplying electrode 1 is such that the two streams impinge upon spaced areas upon the cupped surface of the second multiplying electrode 2 . Here again, a multiplication by reason of secondary emission is secured and this is repeated in any 10 desired number of stages until the amplified and still separate modulated and unmodulated streams of secondary electrons are collected upon the inclined surfaces of the anodes B , B' , respectively.

15 It will be observed from an inspection of the drawing that voltages applied to the multiplying electrode 6 and to the auxiliary anode B' are derived from that portion of the voltage divider which is constituted by resistors $r1$, $r2$ and $r3$. 20 Thus, any change in the electron current to the auxiliary anode B' will give rise to a counter change in the potential applied to electrode 6 . This is so because the electron current to and from electrode 6 is negligible when compared to the current flowing through resistors $r2$ and $r3$, and because the current flowing through electrode B' , when the cathode is illuminated, is large compared to the current drawn through resistor $r1$ when the cathode is unilluminated. 25 Therefore, an increase or decrease in the current to B' when the device is in operation will give rise to a similar change in the voltage across $r1$ and an opposite or compensating change in the voltage drop between the negative terminal of the voltage divider and the point to which electrode 6 is connected. If the point $\pm 6V$ to which electrode 6 is connected is properly chosen (between the values of $5V$ and $7V$) a change in the control voltage applied thereto will result in a change in the focus or refocusing of the electron streams required to compensate for changes in the focusing which occurs by reason of undesired variations in the gain of the device. 35 Thus, the modulated current which flows from the main anode B to the output impedance Z and meter M is stabilized.

40 Various modifications of the invention will suggest themselves to those skilled in the art. It is to be understood, therefore, that the foregoing is to be interpreted as illustrative and not in a limiting sense except as required by the prior art and the spirit of the appended claims.

45 What is claimed is:

50 1. Method of controlling the gain of an electron-multiplier device which comprises generating two discrete electron streams in said device, directing said discrete electron streams to different areas of a common multiplying electrode, separately collecting the resulting multiplied electrons comprising each of said streams, and then controlling the passage of one of said electron streams through said device by the current resulting from the collection of the electrons comprising the other of said electron streams. 55

60 2. Method of controlling the gain of an electron-multiplier device which comprises simultaneously producing a signal bearing and discrete non-signal bearing stream of electrons in said device, directing said discrete electron 65

- streams to different areas of a common multiplying electrode, separately collecting the resulting multiplied electrons comprising each of said streams and then controlling the passage of said streams 5 and then controlling the passage of said signal bearing electron stream through said device by the current resulting from the collection of the electrons comprising said non-signal bearing electron stream.
3. Method of controlling the gain of an electron-multiplier device which comprises generating two discrete electron streams in said device, directing said discrete electron streams to different areas of a common multiplying electrode, separately collecting the resulting multiplied 10 electrons comprising each of said streams and then controlling the multiplication of the electrons comprising one of said streams by the current resulting from the collection of the electrons in the other of said streams.
- 20 4. Method of controlling the gain of a photo-sensitive electron-multiplier device which comprises producing two separate light beams, impressing a signal on one of said light beams, causing the signal bearing and the non-signal bearing light beams to respectively produce a signal bearing and a non-signal bearing electron stream, directing said electron streams to different areas on a common multiplying electrode, separately collecting the resulting multiplied 25 electrons comprising said streams, and then controlling the passage of said signal bearing electron stream through said device by the current resulting from the collection of the electrons comprising said non-signal bearing electron stream.
- 30 5. The combination with an electron multiplier comprising a cathode, a multiplying electrode and a plurality of separate collecting electrodes mounted within an evacuated envelope, of means for generating a plurality of discrete elec- 35
- tron streams in said envelope, means for directing said discrete electron streams to different areas upon said multiplying electrode and thence to said separate collecting electrodes, and means responsive to the current resulting from the collection of the electrons comprising one of said electron streams for controlling the passage of the other of said electron streams through said device.
6. The combination with an electron multiplier 10 comprising a cathode, a multiplying electrode and a plurality of separate collecting electrodes mounted within an evacuated envelope, of means including said cathode for simultaneously generating a signal bearing and a discrete non-signal bearing electron stream in said envelope, means for directing said discrete electron streams to different areas of said multiplying electrode and thence to said separate collecting electrodes, and means responsive to the current resulting 15 from the collection of the electrons comprising said non-signal bearing stream for controlling the passage of said signal bearing electron stream through said envelope device.
7. The combination with an electron multiplier 20 comprising a cathode, a multiplying electrode and a plurality of separate collecting electrodes mounted within an evacuated envelope of means including said cathode for generating a plurality of discrete electron streams in said envelope, 25 means for directing said discrete electron streams to different areas upon said multiplying electrode and thence to said separate collecting electrodes and means responsive to the current resulting from the collection of the electrons comprising one of said electron streams for controlling the multiplication of the electrons in the other of said streams.
